UNITED STATES PATENT OFFICE.

EARL F. HAUSERMAN, OF CLEVELAND HEIGHTS, LEROY D. MOWERY, OF CLEVELAND, AND JOHN A. BOHNSACK, OF EAST CLEVELAND, OHIO, ASSIGNORS TO THE E. F. HAUSERMAN COMPANY, OF CLEVELAND, OHIO, A CORPORATION OF OHIO.

INTERCHANGEABLE PARTITION INSERT.

Application filed September 7, 1928. Serial No. 134,113.

This invention relates to wall-construction sections, and more particularly sections providing openings. In wall or partition construction and especially in metal-frame 5 glass panel walls or partitions, it is desirable in some situations to have available small window-like sections capable of being opened temporarily or permanently as may be required. To the accomplishment of such and 10 related objects, the invention, then, consists of the means hereinafter fully described, and particularly pointed out in the claims. The annexed drawings and the following description set forth in detail certain features 15 embodying the invention, such disclosed features constituting however, but a few of various forms in which the principle of the invention may be used.

In said annexed drawings:—

20 Fig. 1 is a front elevation of a portion of wall or partition constructed in accordance with the invention; Fig. 2 is a section on larger scale and partially broken to accommodate to space limitations; Fig. 3 is a detail in elevation; Fig. 4 is a sectional detail; Fig. 5 is a front elevation of a modification; Fig. 6 is a vertical section of the same on a larger scale; Fig. 7 is a transverse section; and Fig. 8 is a sectional detail of a further 25 modification.

In its general aspects, the invention comprises a sectional framing and a movable or openable panel unit. Preferably, such unit is interchangeable in the general wall or 30 partition system. That is, the framing 1, 2 comprising upright and horizontal members may be laid out to standardized dimensions to receive metallic or glass panel sections of 35 convenient uniform size, and any of these 40 may be substituted by the openable units to be described. This is facilitated by the character of the framing which generally will comprise shouldered channeled muntin cap members 3 (see Fig. 7) or 4 (see Fig. 4) 45 removably secured to channeled muntin members 5, as by screws 6 or the like, the shoulders of the member 5 and the member 4 being spaced apart sufficiently to receive 50 therebetween the edge of the panel stretcher 7, which may be of metal, fiber composition or glass as desired. Otherwise expressed, the framing has grooves lying with-

in its general plane, such grooves being adapted to receive the edges of the panel members.

55 Since the grooves may be readily opened up in effect, as seen, by the removal of the facing portion or muntin cap, it thus becomes possible to take out at any point desired a panel which has already been placed 60 and substitute the openable section, or such section may be built in place when the wall or partition is being initially set up. After removing a panel section, the muntin cap member 3 may be replaced and the openable 65 unit may be mounted in connection with the groove so left, or in some instances, the muntin member 3 may be replaced by the member 4 which differs slightly in that one shoulder instead of being set to space back 70 from the shoulder of the channeled member 5 here extends sufficiently far to abut directly against the shoulder of such member, and thus, as shown in Fig. 4, present a smooth finished surface at the edge receiving the movable section. With this form, the movable section is swingably mounted, generally with swing pivots above and below although the precise location of these 75 may of course be somewhat varied. Conveniently, the bearing plate 8 having legs 9, which may be slightly offset from the plane of the plate but parallel therewith, and carrying a pivot pin 10, provides the principal hinge element. Such elements are secured within the grooves 11 of the framing, screws 12 or the like being passed through the legs into the framing, and coacting with the pivot pins 10 are plates 13 which are secured as by welding or other convenient 80 means to the rails of the swingable panel. These rails as well as the stiles comprise hollow sheet metal members 14 having an integral shoulder 15 against which the panel stretcher is secured by angle members 16, 85 screws 17 or the like being provided at suitable intervals therefor. The panel stretcher element may be of glass or metal or other material as desired but ordinarily will be a 90 glass construction.

100 Where the openable section is preferred more on the order of a wicket, the same general construction, that is, the rails and stiles made up of hollow sheet metal members 14

with the integral shoulder 15 and the stretcher or filler of glass 8 or other material secured by the angle pieces 16 is employed, and for mounting, the muntin cap elements 3 are retained and in the groove left between the shoulders of the muntin members 3 and the channeled muntin member 5, there may be secured hinge supports 18, these being conveniently fastened by screws 19 or the like to the shoulder of the channeled muntin member 5. Hinges 20 then directly support the swingable section, and for latching the section in closed position where desired, a latch 21 of spring actuated type may be secured to the swingable section and a catch 22 coacting therewith may be fastened to the framing as by screws 23 taking into the shoulder of the member 5 and thus within the general groove of the framing members. 20 A shelf 24 is generally desirable in this connection and this may be stamped up of sheet metal with a strengthening flange 25 at the margin, and the entire plate may be held in position by a backing bracket 26 secured to the shelf plate by welding or other suitable means and being held in turn to the framing by screws 27 or the like passing through a reenforce 28 held to the framing by screws or the like 29 within the framing groove.

30 The stop or strike may be positioned on the muntin or frame member 5 as at 30, Fig. 7, or in some instances it is desirable to position it on the swinging element as at 31, 35 Figs. 4 and 8, it being then a folded flange extension, or a flange secured by welding or other suitable means.

It is thus seen that the openable element may be made up in more or less elaborate form as the particular circumstances in any situation may dictate and the construction in general presents an easily set up and convenient interchangeable arrangement of attractive form fitting in with the general scheme of the wall or partition as a whole.

45 Other modes of applying the principle of the invention may be employed instead of those explained, change being made as regards the features herein disclosed, provided the means stated by any of the follow-

ing claims or the equivalent of such stated means be employed.

We therefore particularly point out and distinctly claim as our invention:—

1. In construction of the character described, the combination of suitable framing, panel sections securable in said framing, muntin members engageable against the face of said panel sections, and a swingable section of less than door size directly adapted to interchangeably fit said framing without dismantling the same, said swingable section comprising hollow stile and rail members, each having an integral shoulder, a stretcher element engaged against said shoulders, angle pieces for securing said stretcher element, and means for mounting said swingable section within said framing.

2. In construction of the character described, the combination of sectional framing having grooves, panel elements engageable in said framing grooves, a swingable section of less than door size directly adapted to interchangeably fit said framing without dismantling the same, said swingable section comprising hollow stile and rail members each having an integral shoulder, a stretcher element engaging said shoulders, angle pieces for securing said stretcher element, and means securable in said framing grooves for mounting said swingable section.

3. In construction of the character described, the combination of sectional framing, panel sections securable in said framing, muntin members engageable against the face of said panel sections, a swingable section adapted to interchangeably fit said framing, a stop for limiting the extent of movement, and a shelf beneath said swingable section.

4. In metallic partition construction, a panel frame adapted to receive glass, a muntin frame adapted to removably fit said panel frame, a swingable frame adapted to fit said muntin frame, and a shelf beneath said swingable frame.

Signed by us this 26 day of August, 1926.

EARL F. HAUSERMAN.

LEROY D. MOWERY.

JOHN A. BOHNSACK.
